CLAIM

The ornamental design for a mobile phone, as shown and described.

DESCRIPTION

FIG. 1 is a front perspective view of a mobile phone showing my design.

FIG. 2 is a bottom rear perspective view of the mobile phone.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view thereof, taken from encircled portion 9 in FIG. 1.

The broken lines in the drawings illustrate portions of the mobile phone, that form no part of the claimed design. The dash-dot broken lines in FIGS. 1 and 9 encircling a portion of the mobile phone form no part of the claimed design.
